UNITED STATES PATENT OFFICE.

JOHANN JACOB KEYSER, OF AARAU, SWITZERLAND.

SPINNING AND TWISTING MACHINE.

Application filed April 7, 1927, Serial No. 181,776, and in Switzerland and Germany April 16, 1926.

This invention is concerned with improvements in spinning, twisting and the like machines, particularly with improvements of the actuating mechanism of the feeding and stretching portion of such machines. In former machines of this kind a pinion gear comprising a considerable number of pinions was arranged between the main actuating shaft and the feeding and stretching mechanism of the machine for operating the same. Only the pinions adjacent to the feeding and stretching mechanism could be exchanged, whereas a modification of the remaining gear train could not be effected. It therefore has already been proposed to use chains for the actuation of the feeding and stretching mechanism instead of pinions which however permitted a variation of the numbers of revolution of the stretching and feeding mechanism by a special speed changing device interposed between the chain gear and the feeding and stretching mechanism.

It is the purpose of this present invention to permit a speed change without any variation of the length of the chain by having the chain transmitting members supported on an adjustable support adapted to be rocked around the axis of the main actuating shaft and to be further rocked over 180° C. around an intermediate bolt or pin normally locked at the main bearing shield of the machine in order to reverse the speed ratio transmitted between the main actuating shaft and the feeding and stretching mechanism.

In the drawing which illustrates a preferred embodiment of my invention

Fig. 1 is a front view of the main bearing shield of a double-sided spinning machine having chain transmission, the cover of the main bearing shield being omitted for the sake of clear illustration,

Fig. 2 is a side view of Fig. 1,

Fig. 3 is a front view of the chain gear on a greater scale,

Fig. 4 is a section on line 4—4 of Fig. 1,

Fig. 5 is a section on line 5—5 of Fig. 3.

The spindles 1 are actuated by worm gears 2 the driving shaft 3 of which is supported in the spindle bearing 4 and driven by an actuating gear 6 located within the main

bearing shield 5. The gears 6 are actuated, respectively, by a main gear 7 and shaft 8, as illustrated, which are driven by pinions 9, shafts 10, couplings 11 and a motor 12, the pinions 6, 7 and 9 being preferably located in casings 14 closed by detachable lids 15, the whole main bearing shield 5 being preferably closed by a detachable cover 16 as shown in Fig. 2. The feeding and stretching mechanism indicated at 17 is operated by a pinion 18 and pinions 20, 21, as shown, which may be adjusted within a slot 19.

A transmission of the actuating power from the shafts 8 of the main gears 7 to the pinions 20, 21 is effected by a chain 22 passing over sprockets 23, 24 supported by pins 25 of a double-armed lever 27. The pins 25 are carried by lugs 26, the lower pin 25 being arranged in alignment with the shaft 8 of the main pinion 7 and so as to rotate therewith and the double-armed lever 27 is supported on a bolt 28 arranged centrally of the axes of pins 25 and guided in a circular T-shaped slot 29 of a lug 30. This slot 29 is concentric with pin 8 and lower shaft 25 and the lever 27 can be locked by bolt 28 in its operative positions as will be readily understood. Upon a 180° rotation of lever 27 around its bolt 28 the upper sprocket will be located in axial alignment with shaft 8 so that it can be coupled with the main pinion 7 for simultaneous rotation as will be explained hereinafter.

In order that the sprockets may be operated by shaft 8 and pinion 7 the pins 25 are at the embodiment illustrated provided with square recesses 31 engaging with the corresponding square ends of shafts 8 so as to rotate therewith. The pins 25 are further provided with extensions adapted to carry and actuate a pinion 32 meshing with pinion 21 in order to drive the feeding and stretching mechanism. The pinion 32 can thus be readily dismounted, when the position of the sprockets is to be reversed, it being understood that that sprocket only which is the upper one at a given adjustment will have to carry the pinion 32 on its pin 25. In the embodiment illustrated the ratio between the two sprockets 23, 24 is 2:3. This ratio may of course be varied as required, care being

taken however that the length of chain 22 remains constant.

From the foregoing description it results, that upon loosening bolt 28 the lever 27 can be turned around the axis of shaft 8 so as to disengage the pinion 32 from pinion 21. The pinions 20, 21 and 32 respectively can now be exchanged in order to provide fine adjustment of the working speed of the feeding and stretching mechanism, whereupon the engagement of the pinions is reestablished and the lever 27 locked by means of its bolt 28. When coarser adjustments are required bolt 28 is again loosened and the lever 27 shifted forward so as to disengage the lower pin 25 from shaft 8. The lever 27 can now be turned over 180° around its bolt 28 and the chain drive reestablished and locked as will be readily understood, whereupon the ratio between the driving and driven parts is reversed. The upper and lower sprockets can thus be reversed in a very quick and simple way, so that the number of intermediate pinions 32, 30, 21, 20 can for a given range of speed adjustment be considerably reduced.

What I claim as my invention is:—

1. In an actuating mechanism for spinning and twisting machines a driving pinion gear, a mechanism to be driven, a chain gear between the said driving gear and the said mechanism and comprising a chain a driving sprocket arranged coaxial with and detachably coupled with a pinion of the said driving gear so as to be driven thereby and a driven sprocket located adjacent to and adapted to actuate the mechanism to be driven, means on either sprocket permitting to couple the same with the said pinion of the driving pinion gear, further means on either sprocket for detachably carrying a pinion adapted to mesh with a pinion of the mechanism to be driven, a support for the said chain gear constituting means for reversing the driving and driven relation of the two sprockets and a detachable pinion on the said driven sprocket for actuating the mechanism to be driven.

2. In an actuating mechanism for spinning and twisting machines a main actuating pinion gear, a chain gear comprising a chain and two sprockets the one of which is adapted to be actuated by the main actuating pinion gear, the other one carrying means for driving a mechanism to be driven, a lever carrying both sprockets and adapted to be rocked around the axis of one sprocket, a pivot for said lever arranged centrally between the two sprockets and permitting a 180° rotation thereof so as to reverse the ratio of the mechanism, and means for locking the said lever.

3. In an actuating mechanism for spinning and twisting machines a driving pinion gear, a mechanism to be driven and a chain

gear between the driving pinion gear and the said mechanism to be driven and comprising two sprockets one of which being located adjacent and coaxial with a pinion of the driving pinion gear the other of which being located adjacent the mechanism to be driven, means on either sprocket adapted to couple the sprocket adjacent to the driving pinion gear with the coaxial pinion thereof, means on either sprocket for detachably carrying a pinion adapted to actuate the mechanism to be driven, a detachable pinion on the sprocket adjacent to the mechanism to be driven for driving the same, a double-armed lever carrying the two sprockets and adapted to be pivoted around the axis of the coaxial pinion, so as to bring the detachable pinion into and out of operative relation with the mechanism to be driven, a pivot for the said lever centrally of the two sprockets and permitting a 180° rotation thereof so as to reverse the ratio of the chain gear and means for locking the said lever in its operative position.

4. In an actuating mechanism for spinning and twisting machines a driving pinion gear, a mechanism to be driven and a chain gear between the driving pinion gear and the said mechanism to be driven and comprising two sprockets one of which being located adjacent to and coaxial with a pinion of the driving pinion gear the other of which being located adjacent the mechanism to be driven, means on either sprocket adapted to couple the sprocket adjacent to the driving pinion gear with the coaxial pinion thereof, means on either sprocket for detachably carrying a pinion adapted to actuate the mechanism to be driven, a detachable pinion on the sprocket adjacent to the mechanism to be driven for driving the same, a double-armed lever carrying the two sprockets and adapted to be pivoted around the axis of the coaxial pinion, so as to bring the detachable pinion into and out of operative relation with the mechanism to be driven, a pivot pin for the said lever centrally of the two sprockets and adapted to be rocked concentric therewith around the axis of the coaxial pinion and permitting a 180° rotation of the said lever so as to reverse the ratio of the chain gear and means for locking the said lever in its operative position.

5. In an actuating mechanism for spinning and twisting machines, a driving shaft, a driven shaft having a pinion thereon, a reversible member between the said shafts, a sprocket wheel mounted in each end of the member and adapted to be coupled with the driving shaft, the sprocket wheels being of different sizes, a chain passing around the sprocket wheels, and a pinion adapted to be connected with either of the said sprocket wheels to turn therewith.

6. In an actuating mechanism for spin-

ning and twisting machines, a driving shaft, a driven shaft having a pinion thereon, a two armed lever pivotally mounted between the said shafts to swing into reverse position, means for locking the lever, a shaft mounted in each arm of the lever and adapted to be coupled to the driving shaft, a sprocket wheel on each shaft, the sprocket

wheels being of different sizes, a chain passing around the sprocket wheels, and a pinion adapted to be secured to the shaft of either of the sprocket wheels to mesh with the pinion of the driven shaft. ¹⁰

In testimony whereof I affix my signature.

JOHANN JACOB KEYSER.
